FUR WRAPPING FOR A PIGTAIL

Marcia Annette Red Fox, 3180 Stark St.,
Eugene, Oreg. 97402

Filed Feb. 22, 1972, Ser. No. 228,449

Term of patent 14 years

Int. Cl. D2—03

U.S. Cl. D86—10 J

FIG. 1 is a front elevational view of a fur wrapping for a pigtale embodying my new design,

FIG. 2 is a rear elevational view,

FIG. 3 is a top plan view, and

FIG. 4 is a bottom plan view.

I claim:

The ornamental design for a fur wrapping for a pigtale, substantially as shown.
